UNITED STATES PATENT OFFICE.

CHESTER D. AINSWORTH, OF WOLLASTON, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS.

ELECTRIC SWITCH.

Application filed September 21, 1927. Serial No. 221,071.

This invention relates to enclosed electric switches especially adapted to carry heavy alternating currents.

The electric switch with which this invention is particularly concerned comprises an oil receptacle and a switch frame which comprises a cover for the oil receptacle. Massive insulated studs are carried by the switch frame and are immersed in the oil in the receptacle and one or more bridging members constituting the movable switch member are disposed in the oil and are movable into and out of engagement with the studs.

The oil receptacle is composed of sheet iron, as boiler plate and is strong to resist the high internal pressures that may be developed upon circuit interruption under heavy load. Under some conditions of operation, as when the switch is called upon to carry an exceptionally heavy current, it is found that the side walls of the oil receptacle become hot and heat is transmitted through the oil to the other parts of the switch and so raises the temperature of the entire switch and thus limits the current carrying ability of the switch. The heat is developed in the side walls of the oil receptacle by hysteresis and eddy currents set up therein since the arrangement of the conducting studs and bridging member is such as to form a U which is practically the equivalent of a one turn solenoid and thus sets up a magnetic flux which acts upon the side walls of the oil receptacle. The side walls are made of sheet iron of a character, as boiler plate, which is not a particularly good magnetic conductor since it has high hysteresis and eddy current losses therein and these internal losses are largely responsible for the heating of the side walls.

It is an object of this invention to reduce the heating of an electric switch of the above type by providing the side walls of the enclosing casing, or of the oil receptacle, with a magnetic shield which is interposed between the conducting components of the switch and the side walls, thereby to shield the side walls from the action of the alternating magnetic flux in the vicinity of the current conducting components of the switch.

A further object of the invention is the provision of a magnetic shield for the wall of the enclosing casing which is characterized

by being composed of material having lower magnetic losses than the material of which the side wall is composed, thus to reduce the heating of the casing.

A further object of the invention is generally to improve the construction and operation of electric switches and equivalent apparatus.

Fig. 1 is a side elevation illustrating two of the three switches of a three phase switching apparatus especially adapted for the control of circuits traversed by heavy currents.

Fig. 2 is a sectional elevation taken along line 2-2 of Fig. 1.

Fig. 3 is a sectional elevation taken along line 3-3 of Fig. 2.

Fig. 4 is a perspective view of one of the oil receptacles of the switch, partially broken away to illustrate the magnetic shield forming a feature of this invention.

Fig. 5 is a perspective view of one of the magnetic shields.

The switch here shown as embodying the invention comprises an oil receptacle 10 of rectangular shape and a cover 12 which is suspended from the box-like casing 14 in which the switch operating mechanism is contained.

The oil receptacle is secured removably to the cover plate or switch frame by bolts and wing nuts 16. The stationary switch members 18 and 20, forming the opposite poles of the switch, comprise a series of horizontally spaced vertical bars 22 which are connected electrically together and are passed through and supported by insulators 24 carried by the switch frame 12. The lower ends of said bars are provided with massive contact blocks 26 which form the stationary contact members of the switch. As here shown, each stationary switch member comprises two sets of bars 22.

The movable switch member comprises a plurality of massive brush members 28 each of which is carried at the lower end of an insulated lifting rod 30 which is connected to the operating mechanism 32. As here shown four brush members 28 are employed conjointly to carry the current between the poles of the switch.

The oil receptacle is composed of sheet iron as boiler plate and has relatively thick side walls 34. Said side walls are relatively closely spaced to the conducting components of the switch and are thus in the magnetic field sur-

rounding said components and thus the side walls become heated by reason of the hysteresis and eddy current losses therein.

In accordance with this invention, I provide a magnetic shield which is interposed between the side walls of the receptacle and the conducting components of the switch for the purpose of shielding said side walls from the magnetic flux of the current carrying components, thus to prevent the generation of heat in the side walls.

The specific magnetic shield herein illustrated comprises two U-shaped members having the legs 36 and 38 and the integral connecting member 40. Said shields are composed of a plurality of laminations of U-shape assembled to form a shield of substantial thickness. The laminations are composed of electrical steel which is characterized by having high permeability and low hysteresis and eddy current losses as compared with the steel of which the oil receptacle is constructed. Said shields are disposed in the opposite ends of the oil receptacle to lie against the inner face of the side wall thereof and the ends of the shield are for convenience in manufacture terminated adjacent each other or are provided with a small vertical space or gap between the opposed legs thereof. The usual insulating lining 42 is disposed within the oil receptacle and against said shields. Said shields are against the side walls of the oil receptacle from a point at the top of the side walls and are extended downwardly at least throughout the zone of the magnetic field surrounding the current conducting components of the switch and preferably are extended down to and rest upon the bottom wall of the oil receptacle whereby to be self-supporting, with the insulating lining 42 holding said shields in place against the side walls of the tank. As thus arranged, the magnetic flux surrounding the conducting components of the switch that ordinarily would pass into the side walls of the oil receptacle is caused to pass through the magnetic shield and is mainly excluded from the oil receptacle. Since the material of the shield has a high permeability and very much lower hysteresis and eddy current losses than the material of the oil receptacle, it is apparent that the generation of heat in the oil receptacle by the alternating magnetic flux will largely be prevented and since the iron losses in the shield are much lower than those in the tank, the losses in the shield will not be high enough to set up any appreciable heating in the shield.

I claim:

1. An electrical apparatus having a current conducting component and a member normally disposed in the magnetic field of said component and liable to be heated by the alternating magnetic flux surrounding said component, and means interposed between said member and said current carrying

component characterized by shielding said member against the magnetic flux surrounding said current conducting component, said shielding means being further characterized by having hysteresis and eddy current losses which are materially less than the corresponding losses of said member. 70

2. An electrical apparatus having an enclosing casing and a current conducting component disposed within said casing and having an alternating magnetic field surrounding it which acts on said casing, and a magnetic shield interposed between said current conducting component and said casing in position to isolate said casing from the influence of said magnetic field. 75

3. An electric switch having an enclosing casing, switch terminals extended into said casing, a movable bridging member disposed within said casing in cooperative relation with said terminals, and a magnetic shield interposed between said terminals and the wall of said enclosing casing. 80

4. An electric switch comprising an enclosing casing having a side wall of magnetic material, stationary and movable switch members disposed within said casing, and a magnetic shield interposed between said switch members and said wall of said casing. 90

5. An electric switch comprising an enclosing casing having an iron side wall, stationary and movable switch members disposed within said casing, and a magnetic shield interposed between said switch members and said wall of said casing, said magnetic shield characterized by having materially lower hysteresis and eddy current losses therein than the said losses of said iron wall. 100

6. An electric switch having an enclosing casing liable to become heated by the alternating flux surrounding the current carrying components of the switch, and means to shield said casing from said magnetic flux. 105

7. An electric switch having an enclosing casing liable to become heated by the alternating flux surrounding the current carrying components of the switch, and means to shield said casing from said magnetic flux, said shielding means being interposed between the current conducting components of the switch and said casing and characterized by having lower magnetic losses therein than the losses in said casing. 110

8. An electric switch having an enclosing casing, stationary and movable switch members disposed in said casing, and a pair of magnetic shields disposed within said casing adjacent the wall thereof and having their ends disposed in proximate relation. 120

9. An electric switch having an oil containing enclosing casing, stationary switch members immersed in the oil in said switch casing, and a magnetic shield interposed between the switch members and the wall of said casing and extended throughout the region 125 130

of magnetic field surrounding said switch members within said casing.

10. An electric switch comprising an enclosing casing having a rectangular oil containing receptacle, stationary and movable switch members immersed in the oil in said receptacle, and a pair of U-shaped magnetic shields disposed within said casing at and overlying the inner face of the side walls thereof and interposed between said side wall and said switch members and having proximate ends.
11. An electric switch comprising an enclosing casing having a rectangular oil containing receptacle, stationary and movable switch members immersed in the oil in said receptacle, a pair of U-shaped magnetic shields disposed within said casing at and overlying the inner face of the side walls thereof and interposed between said side wall

and said switch members and having proximate ends, and an insulating lining disposed within said oil receptacle and said magnetic shields.

12. An electric switch having an enclosing casing provided with a side wall of magnetic material, stationary and movable switch members disposed within said casing, and a magnetic shield disposed within said casing and interposed between said switch members and the side wall of said casing, said magnetic shield composed of a plurality of laminations of magnetic material characterized by having higher permeability and lower magnetic losses than the material of said side wall.

In testimony whereof, I have signed my name to this specification.

CHESTER D. AINSWORTH.
